UNITED STATES PATENT OFFICE

127,905

DESIGN FOR A BUILDING

Ernest Merrell Ellis, Portland, Oreg.

Application March 25, 1939, Serial No. 83,822

Term of patent 3½ years

To all whom it may concern:

Be it known that I, Ernest Merrell Ellis, a citizen of the United States, residing at Portland, in the county of Multnomah and the State of Oregon, have invented a new, original, and ornamental Design for a Building, of which the following is a specification, reference being had to the accompanying drawings, forming part thereof.

Fig. I is a front perspective view of the building, showing my new design.

Fig. II is a rear elevation of the building.

Fig. III is an end elevation of the building.

Fig. IV is a side elevation of the building.

I claim:

The ornamental design for a building, as shown.

ERNEST MERRELL ELLIS.
